2 SHEETS--SHEET 2.

UNITED STATES PATENT OFFICE.

HARRY B. ROSS, OF BENTON HARBOR, MICHIGAN.

MOTOR-VEHICLE.

1,271,946.

Specification of Letters Patent. Patented July 9, 1918.

Application filed December 4, 1916. Serial No. 134,801.

To all whom it may concern:

Be it known that I, HARRY B. Ross, a citizen of the United States, residing at Benton Harbor, in the county of Berrien 5 and State of Michigan, have invented certain new and useful Improvements in Motor-Vehicles, of which the following is a specification.

This invention relates to motor vehicles, 10 and its object is to provide improved devices for resiliently supporting the vehicle body and afford thereto independent movement relative to the running gear and also with respect to the power-transmission mechanism to enable the vehicle to travel steadily over uneven ground.

A further object is the provision of a novel mounting for the traction wheels whereby they may be individually raised without disturbing the driving mechanism or tilting the 20 vehicle laterally.

With these and other ends in view, the invention consists in the novel construction and combination of parts, as will be herein- 25 after described and claimed.

In the accompanying drawings, Figure 1 is a side elevation of the rear portion of a motor vehicle embodying the present invention. Fig. 2 is a rear elevation of the same 30 with parts shown in section, taken substantially through 2—2 of Fig. 1. Fig. 3 is a fragmentary view of the vehicle body frame and driving mechanism, shown partly in plan and partly in section, said section being on line 3—3 of Fig. 1. Fig. 4 is a detail sectional view on broken line 4—4 of Fig. 1. Fig. 5 is a side elevational view of the lower 35 end of one of the radius rods.

The vehicle body, illustrated in the drawings, is formed with a rigid framework having longitudinal beam members 6, 6¹ and 6² connected near their ends to upright post members 7 and 7¹, and transverse beam members 8 and 8¹ disposed in proximity to the 40 upper ends of said post members, the latter at each side being secured at their lower ends in spaced relations by a plate element 9.

By such construction, there is provided a body of substantially an inverted U - shape 45 in cross-section to afford a tunnel-like opening A (Fig. 2) between two side legs B. Below each of said legs is a rectangular frame formed of side plates 10 and end plates 11. This frame is hingedly connected, 50 as at 12, from one of its ends to the adjacent leg B and has at its other end a tongue

13 which extends into a vertically disposed guide 14 secured to the leg.

15 represents helical springs provided between each of the body legs and the free end 60 of the subject frame. Rigidly secured, as by bolts 16, to the plates 10 of each frame, are bearing boxes 17 for the journal ends provided on the hub 18 of a ground or traction wheel 19.

20 represents a bolt extending through the hub 18 and the frame plates 10 to prevent the latter from spreading apart. Fixedly secured to each wheel hub is a sprocket wheel 21 whereby the respective traction wheel is 70 driven through the agency of a chain 22 extending down in the respective leg from a sprocket wheel 23 provided on a transversely arranged stub shaft 24. These shafts are journaled at each side of the vehicle in 75 bosses 25 provided on the forward ends of complementary arms 26 which are coupled by a bolt 27 (Fig. 3) and pivotally supported at their other ends by a pin 28 which is connected with the body framework, as 80 shown.

The stub shafts 24 may be driven in any suitable manner as, for example, by means of a system of differential gears and a train of spur gears 29, 29¹ operatively connecting 85 a pinion 30 provided on the armature shaft of a motor 31 with a spur gear 32 which serves as the driving element of said system of differential gears and carries the equational pinions 37. The stub shafts 24 are each 90 connected by shafts 24¹, and 24² and universal couplings 38 with the driven element 39 of the differential gears.

To compensate for the relative movements of the traction wheels and to maintain stub 95 shafts at different distances from the adjacent traction wheels, I provide radius rods 33. Each of these radius rods has an eye 34 at its lower end to receive a boss 17¹ provided on one of the boxes 17 and at its upper 100 end is bifurcated, as shown in Fig. 2, each branch being bored to fit the bosses 25 of the stub-shaft carrying arms 26.

The lower part of each of said radius rods is desirably provided with arcuate slots 35 105 (Fig. 5) to accommodate bolts 36 connected to the adjacent frame plate 10 and serving to obviate any torsional movements of the lower end of a rod.

From the foregoing, it is seen that the stub 110 shafts 24 of the driving mechanism are supported by the radius rods which engage the

journal boxes of both the respective stub shafts and the wheel axles. These radius rods, as well as the drive chains, are inclosed within the respective vehicle legs.

5. What I claim, is—

1. In a motor vehicle having a body of an inverted U-shape in transverse section, a frame provided under each leg of said body and hingedly connected at one of its ends 10 to the respective leg, a spring interposed between the other end of the frame and the adjacent leg, a traction wheel carried in each frame, transversely arranged vertically movable power-driven shafts provided on the 15 body, a radius rod connecting said shafts with the subjacent frames, and power-transmission devices operatively connecting the shafts with the respective wheels.
2. In a motor vehicle having a body of an inverted U-shape in transverse section, traction wheels connected to the side members of the body for vertical movements independently of each other and relatively of said body, power-driven means provided on the 25 upper portion of said body, and power transmission devices extending from said driven means down through the aforesaid side members to drive the wheels.
3. In a motor vehicle having a body of an inverted U-shape in transverse section, traction wheels connected to the side members of the body for independent vertical movements, power-driven means provided on the 30

upper portion of said body, power transmission devices extending from said driven means down through the respective side members to drive the wheels, and means actuated by the relative vertical movements of the wheels with respect to said body to effect movements to said power-driven means corresponding to the respective wheels.

4. In a motor vehicle, the combination with the vehicle body, traction wheels, frames carrying said wheels and connected with the body for relative vertical movements, and means provided on said frames for yieldingly supporting the body, of power-driven shafts, arms pivotally connected with the body adjacent to the sides of the latter and provided at their free ends with journal bearings for the shafts, driving connections between said shafts and the wheels, and a radius rod connecting each of said frames with the respective arms where-by the latter are influenced by the relative movements of the frames to maintain the shafts at definite distances from the axes of the respective wheels.

Signed at Benton Harbor, Mich., this 23 day of Nov., 1916.

HARRY B. ROSS.
